CLAIM

The ornamental design for a faucet, as shown and described.

DESCRIPTION

FIG. 1 is a left, top, front perspective view of a plumbing faucet embodying my new design;

FIG. 2 is a front elevational view thereof;

FIG. 3 is a top plan view thereof;

FIG. 4 is a left side elevational view thereof, the right side elevational view being a mirror image of the left side shown;

FIG. 5 is a rear elevational view thereof;

FIG. 6 is a bottom plan view thereof;

FIG. 7 is a left, top, front perspective view of a second embodiment which is identical to the first embodiment but for the rear linkage;

FIG. 8 is a front elevational view thereof;

FIG. 9 is a top plan view thereof;

FIG. 10 is a left side elevational view thereof, the right side elevational view being a mirror image of the left side shown;

FIG. 11 is a rear elevational view thereof; and,

FIG. 12 is a bottom plan view thereof.

The broken line representations of holes in FIGS. 1, 4, 5, 7, 10, and 12 are for the purpose of illustration only, and form no part of the claimed design.
